CLAIM

The ornamental design for a water-purifying apparatus, as shown and described.

DESCRIPTION

FIG. 1 is a perspective view of a new design for a water-purifying apparatus;

FIG. 2 is a front view thereof;

FIG. 3 is a right view thereof;

FIG. 4 is a left side view thereof;

FIG. 5 is a rear view thereof, shown in a position of use;

FIG. 6 is a top view thereof, shown in a position of use; and,

FIG. 7 is a bottom view thereof.

The elements shown in broken lines form no part of the claimed design.

1 Claim, 7 Drawing Sheets
